UNITED STATES PATENT OFFICE.

WALLACE S. CLARK AND GEORGE H. RUPLEY, OF SCHENECTADY, NEW YORK, ASSIGNORS TO THE GENERAL ELECTRIC COMPANY, A CORPORATION OF NEW YORK.

INSULATED ELECTRIC CONDUCTOR AND PROCESS OF MAKING SAME.

SPECIFICATION forming part of Letters Patent No. 687,517, dated November 26, 1901.

Application filed December 15, 1899. Serial No. 740,402. (No model.)

To all whom it may concern:

Be it known that we, WALLACE S. CLARK and GEORGE H. RUPLEY, citizens of the United States, residing at Schenectady, county of 5 Schenectady, State of New York, have invented certain new and useful Improvements in Insulated Electric Conductors and Processes of Making the Same, (Case No. 1,294,) of which the following is a specification.

10 The object of the present invention is to permit the manufacture of an electric conductor covered with a dense, coherent, elastic insulating material which may be applied so as to envelop the conductor when desired 15 in a thin skin or film.

A further object of the invention is to cheapen the manufacture of insulated conductors and to enhance their insulating properties while reducing the space occupied by 20 the insulation, thereby permitting a greater bulk of conducting material to be inclosed in a given space in electrical apparatus.

In carrying out our invention we place upon 25 the conductor a uniform coating containing a compound of an amorphous or structureless cellulose and retard its drying after being applied to the conductor, thereby insuring a uniform thickness of the film or coating and intimate and uniform adhesion between the 30 coating and the surface of the conductor; also, a toughening of the covering and absence of cracks due to uneven shrinkage. We employ a soluble compound of cellulose, to which we add a vehicle, which will combine with the solvent, 35 of slow drying or evaporating qualities relatively to the solvent and mix the ingredients in such proportions as to form a compound fluid at the working temperature and lead the conductor into contact with the compound, whereby the latter is covered with a thin film, and as it is lead away from the bath or coating apparatus the coating is evenly distributed around the conductor and the latter then lead through a drying apparatus and 40 wound upon a reel. We have obtained the best results thus far by employing a solution 45 of pyroxylin in methyl alcohol, to which sufficient amyl acetate has been added to retard the drying. If the alcohol alone be employed 50 as a solvent, its highly-volatile character per-

mits an ineffective application of the amorphous cellulose compound to the conductor and leaves the coating in a poor condition to withstand service. A rapid drying tends to crack the coating, leaving it valueless as an 55 insulating medium, particularly where exposed to water or damp air, and leaves it brittle and liable to crack and chip off under flexure of the conductor. The addition of the amyl acetate adds toughness to the coating 60 and gives it an elasticity which prevents cracks in drying and permits it to withstand bending of the conductor.

Our invention, however, is not limited to the application of a solution of pyroxylin, 65 but includes also other amorphous compounds of cellulose known to the arts, or pure structureless cellulose derived from cotton or other vegetable fiber, the essential feature of our invention being the application of a solution 70 of an amorphous cellulose compound in such a way as to render the compound non-brittle when dry.

Our invention may be carried out by the employment of a variety of apparatus; but the 75 form we have found effective in practice comprises a bath of coating material in which revolves a grooved wheel to pick up the insulating material, the top of the groove projecting above the bath, and devices for leading the conductor tangentially to the groove. By this organization good distribution of the 80 coating material on the conductor is effected. The conductor is led to the grooved wheel from the supply-reel, and after being coated 85 is carried through a drying box or chamber, and then passes through a testing-bath for locating any defective spots in the insulation, after which it is wound upon a receiving-reel ready for shipment. 90

Other novel features of our invention will be more fully described hereinafter and will be definitely indicated in the claims.

In the accompanying drawings is shown a 95 convenient apparatus for carrying out our improvements.

Figure 1 is a diagram showing the mode of procedure in insulating conductors according to our improvements. Fig. 2 is a plan view of a machine adapted to carry out the improve- 100

ments. Fig. 3 is a side elevation of the same, and Fig. 4 is an end elevation.

No claim, however, is herein made to the improvements in the machine, said matter 5 being reserved for a companion application copending herewith and a division hereof, Serial No. 41,341, filed December 28, 1900.

Referring first to Fig. 1, 1 represents a supply-reel upon which the naked wire to 10 be insulated is wound. From this reel the wire is led over a grooved wheel 2, mounted to revolve in a bath 3 of insulating compound. The consistency of the compound will vary somewhat with the size of the conductor. For 15 a very fine conductor a solution of twelve ounces of pyroxylin in thirty-six of methyl alcohol, to which has been added fifty-two of amyl acetate, gives effective results, permitting a suitable and effective coating on the 20 conductor of about .0005 inch in thickness. The material is carried up from the bath in the peripheral groove of the wheel 2, any excess being scraped off from the edges of the groove by a scraper or knife 4. The conductor passes through the groove so as to bear 25 upon its bottom, the groove being of sufficient depth to submerge the conductor in the insulating material carried around thereon. From this it will be evident that the material 30 is not in a freely mobile fluid condition, but is sufficiently viscous to prevent rapid flowing away from the groove during the rotation of the wheel 2. A scraper 5 may be employed in the bath to remove the partially- 35 dried accumulations of material from the groove. After the application to the wire by the wheel the material firmly adheres and floods all the parts of the surface, making an intimate contact therewith. The wire 40 thus coated is led over a drying-trough, which may be a chamber or a mere heated surface. This heater is indicated at 6 7, representing a row of gas-jets or other source of heat impinging on its under side. The conductor then passes over suitable guides and 45 is led through a testing-bath 8, which may be mercury or water, after which it is wound upon a receiving-reel 9. The bath may be inclosed in a metal vessel electrically connected with a relay 10, controlling an alarm or other indicator 11. A battery 12 or other 50 source of electromotive force may be applied to the reel 1, so as to include the wire in the circuit. Thus when any break occurs in the 55 insulation the testing-circuit is closed and the relay operated, giving notice to the workman that a defective point in the insulation is passing through the testing-bath, when it may be tagged for subsequent treatment.

60 Referring to Figs. 2, 3, and 4, which illustrate an assembled machine for carrying out the operations indicated in the diagram of Fig. 1, 13 represents a drive-shaft to which power may be applied by a pulley 14 and 65 transmitting motion through a train of gears to the reel 9, mounted loosely on its shaft, but prevented from freely turning by a light

friction-brake 15, the pressure of which may be varied by a set-screw, as indicated in Fig. 2. A train of gearing communicates motion to the shaft, on which is mounted the grooved coating-wheel 2, and to a guide-wheel 16 for leading or guiding the wire to the coating-wheel 2. Motion is communicated to a grooved feed-guide 17 for the receiving-reel 75 9, (see Figs. 2 and 4,) carried by a nut fed along a screw 18, to which a reciprocating motion is communicated by means of a straight and a crossed belt, respectively, (indicated at 19 and 20,) one or the other of which is thrown into clutch with the shaft on which the screw 18 is carried. The belts are alternately thrown into operation by a clutch 21, (see Figs. 2 and 4,) adapted to lock one or the other of the loose pulleys 22 23 to the 80 screw-shaft. These pulleys are provided with a spider adapted to receive a projection on each side of the clutch 21. The clutch is shifted by a bar 24, carried on a sliding rod 25, on which are fastened two collars 26 26^a, 85 alternately engaged by a projection 27 from the traveling nut on the screw-shaft 18. The position of these nuts may be controlled by a set-screw, so as to vary the length of receiving-reel on which the wire may be wound. 95 A pivoted bar 28, carrying a roller 29, journaled in its free end, co-operates with a double cam 30, fixed to the shaft 25 to hold the clutch 21 in engagement with the pulley to which it has last been connected until the last turn of 100 wire on that layer is wound, after which the arm 27 reaches the opposite limit of traverse and disconnects the clutch 21 from the pulley it engages and effects connection with the other pulley. The cam 30 and roller 29 permit the clutch to be shifted into engagement 105 with the loose pulley and bear against the same under the thrust of roller 29 until the lateral projection can enter an opening in the spider or face of the pulley. 110

What we claim as new, and desire to secure by Letters Patent of the United States, is—

1. The process of insulating electric conductors, consisting in coating the same with a thin film of amorphous cellulose compound in 115 a slowly-drying solution.

2. The process of insulating electric conductors, consisting in coating the same with a solution of an amorphous cellulose compound in a volatile solvent, and retarding the drying of the applied compound. 120

3. The process of insulating electric conductors, consisting in coating the same with amorphous cellulose compound treated with a solvent containing amyl acetate. 125

4. The process of insulating electric conductors, consisting in coating the same with a thin film of a liquid cellulose compound mixed with a toughening material.

5. The process of insulating electric conductors, consisting in coating the same with a solution of pyroxylin containing amyl acetate. 130

6. The process of insulating electric con-

ductors, consisting in coating the same with a solution of structureless cellulose containing amy1 acetate.

7. The process of insulating electric conductors, consisting in coating the same with a film of amorphous cellulose compound, retarding the drying of the compound until the conductor and coating are in intimate contact and uniform relation, then drying the

coating by heat.

8. As an article of manufacture, an insulated electric conductor coated with a closely-adherent non-brittle, homogeneous covering containing or composed of amorphous cellulose.

9. An electric conductor coated with a film

of homogeneous amorphous cellulose compound.

10. An electric conductor coated with a thin film of homogeneous amorphous cellulose compound and amy1 acetate.

11. An insulating compound for electric conductors consisting of a liquid structureless cellulose compound containing a toughening material.

In witness whereof we have hereunto set our hands this 13th day of December, 1899.
